CLAIM

The ornamental design for a stage light, as shown and described.

DESCRIPTION

FIG. 1 is a perspective view of a stage light design showing my new design.

FIG. 2 is a front view of a stage light.

FIG. 3 is a rear view of a stage light.

FIG. 4 is a left side view of a stage light.

FIG. 5 is a right side view of a stage light.

FIG. 6 is a top view of a stage light.

FIG. 7 is a bottom view of a stage light; and,

FIG. 8 is an enlarged view of a stage light taken from the circled part in FIG. 4.

The shading and cross-hatching are not features of the design but are utilized to illustrate the surface contours of the stage light design in the drawings.

The broken lines in the drawings depict portions of the stage light that form no part of the claimed design.
